UNITED STATES PATENT OFFICE.

FREDERICK JOHN HARBRIDGE, OF GRAVENHURST, CANADA.

CYLINDER PRINTING-PRESS.

SPECIFICATION forming part of Letters Patent No. 664,744, dated December 25, 1900.

Application filed March 9, 1899. Serial No. 708,415. (No model.)

To all whom it may concern:

Be it known that I, FREDERICK JOHN HARBRIDGE, printer, of the town of Gravenhurst, in the district of Muskoka, in the Province of Ontario, Canada, have invented certain new and useful Improvements in Cylinder Printing-Presses, of which the following is a specification.

My invention relates to improvements in cylinder-presses; and the objects of the invention are, first, to provide a delivery for the sheet by which it may be expeditiously taken from the machine without the aid of the impression-cylinder, and thereby effect an economy 10 of time in the delivery of the sheet, and, further, so deliver the sheet that it will be deposited on the receiving-table with the printed side up; secondly, to provide a positive means for insuring the sheet being gripped and 15 held onto the cylinder, and thereby effect a perfect register; thirdly, to provide a simple means for raising the impression-cylinder on its return movement, and, furthermore, an effective throw-off for such cylinder, and, 20 fourthly, to provide a simple, accurate, and very fine adjustment for the type-bed whereby the impression may be regulated to a nicety. These various objects are carried out by the construction of the machine arranged and operating as a whole and in detail as hereinafter more particularly explained.

For the purpose of clearly setting forth the construction of my machine and the advantages to be derived therefrom I have shown my invention in the accompanying drawings, in which—

Figure 1 is a perspective view of my printing-press complete. Fig. 2 is a longitudinal vertical section looking from the same side as Fig. 1. Fig. 3 is a longitudinal vertical section looking from the opposite side of the machine. Fig. 4 is a detail of the sheet-releasing trip. Fig. 5 is a perspective detail of the trip for operating the gripping-fingers to grasp the sheet from the feed-table. Figs. 5^a and 5^b are end views of the cylinder, showing the position of the trip-fingers when the cylinder is at the delivery end and feed-table end, respectively, of its movement. Fig. 6 is a detail of the far cylinder-supporting reciprocating standard shown in Fig. 1. Fig. 7 is a detail of the means for reciprocating the

ink-distributing rollers. Fig. 8 is a detail of the peripheral cam on the counter-shaft controlling the movement of the ink-distributing rollers. Fig. 9 is a detail of the arm and ratchet mechanism for operating the ink-roller in the ink-fountain. Fig. 10 is a detail of the sheet-raising device. Fig. 11 is a detail of the cylinder.

In the drawings like characters of reference indicate corresponding parts in each figure.

A is the main frame of the machine, which is formed in any approved manner and particularly as hereinafter explained.

B is the main driving-shaft of the machine, which is provided with a driving gear-pinion B', which meshes with a gear-wheel C' on the counter-shaft C, from which latter shaft the principal moving parts of the machine derive 70 their operation.

D is the feeding-table, which is pivotally supported at the front end of the machine by the pins d in the frame, as indicated. The table D is wedge-shaped in cross-section, presenting a fine edge near where the paper is delivered to the cylinder, as indicated.

E is the cylinder, which is hollow and is secured on a cross-shaft F, which is supported in the eccentric bearing-sleeves f, journaled 80 in the sliding standards G. The outer ends of the shaft F extend into the blocks f', which are located in the slots h at the upper ends of the swinging arms H, which are pivoted at the bottom on the cross-rod H', extending 85 from side to side of the frame of the machine and outside of the same.

I is a pitman connected at one end to the gear-wheel C' and at the opposite end to the swinging arms H. By means of this pitman 90 I the arms are given their swinging movement backward and forward, thereby imparting to the cylinder its longitudinal reciprocating movement between the feeding-table D and the delivery-table J. (Shown in dotted lines 95 in Fig. 2.) Secured to the shaft F is a gear-wheel K, which meshes with a rack k, attached to or forming a portion of one of the side bars of the frame of the machine.

L is the bed-plate, upon which the type, 100 which is set in the usual manner in a chase, is placed, and 1 represents the tracks at the side of the bed-plate, which support the collars 2', 3', and 4' on the end of the inking-roll-

ers 2, 3, and 4. The track 1 serves to keep the inking-rollers in a proper level position as they pass over the face of the type.

2², 3², and 4² are the spindles of the inking-rollers, which are connected by the rods 4³ and 5 at the ends of the spindles to the bar M, which is pivotally supported at the bottom on the ends of the cross-shaft N, suitably journaled in the frame of the machine. Only one bar M is shown and its complement of rods 4³ and 5. The rods 4³ and 5 extend through the bent ends m of the bar M and are tensionally held by the spiral springs 6 and 7, abutting the upper bent end m and connected at the opposite end to the rods 4³ and 5. The rollers 2, 3, and 4 derive their reciprocating movement over the bed by means of the bar M, which is connected by the rod m' to the lower end of the lever M², which is pivoted at the top at M'. The roller m² is journaled on a stud on the lever intermediate of its length and is designed to be given a forward-and-backward movement by means of the cam-groove C². (See full lines in Fig. 3 and dotted lines in Fig. 1.)

During the period that the roller is in the portion of the cam-groove eccentric to the shaft C the inking-rollers necessarily derive their reciprocating movement across the bed, but during the period that the roller is in the concentric portion such inking-rollers will remain directly over the ink-distributing roller O. The inking-rollers are controlled by the cam-shaped groove C², in which a roller m² on the arm M² moves. This through the pitman connection m' causes the rollers to move from the position shown in Fig. 1 very rapidly, as the cam-groove has a sharp throw. The rollers 2, 3, and 4 then rest at the delivery end of the press during nearly half a revolution of the wheel C', the rollers not beginning their return movement until the cylinder E has completed half of its return movement.

The ink-distributing roller O is supported in suitable bearings by means of the spindle O'. A bevel-pinion o is provided on the spindle at one end thereof, such bevel-pinion being engaged by a similar pinion o' on the end of the spindle o², which is journaled in suitable bearings in the frame. The opposite end of the spindle o² is provided with a bevel-wheel o³, which meshes with a bevel gear-wheel P, secured on the counter-shaft C. The bevel-wheel P is of sufficient diameter so as to drive the ink-distributing cylinder O sufficiently fast to properly and evenly convey the ink to the inking-rollers 2, 3, and 4 when they are brought in contact with it.

Q Q' are the minor distributing-rollers, which abut the major roller O. The minor rollers Q and Q' are provided with spindles q and q', which extend through the reverse obliquely-set slots r r' in the end supporting-brackets R. It is necessary for the proper distribution of the ink that these minor rollers Q and Q' be given an endwise movement alternately,

and in order to provide for this I secure on one of the ends of the spindle the grooved collars q² and q³.

To the bottom of the bracket R, I secure a bar r² and pivoted at the free end thereof the rocking bar r³, which is provided with upwardly-extending pins r⁴ and r⁵, (see dotted lines,) which extend into the grooves of the collars q² and q³, respectively. One end of the rocking arm r³ has pivotally connected to it the lever S, which is pivoted at s on the frame and has a pin or roller s' at the front end, which extends into a cam-groove t of the cam-wheel T, secured to the counter-shaft C. (See Figs. 2 and 8.) By means of this peripheral cam-groove t of the cam-wheel T it will be seen that the lever S is rocked on its pivot, and its opposite end conveys a like rocking motion to the rocking bar r³, and consequently a reciprocating motion alternately in opposite directions to the minor rollers.

U is an intermediate minor ink-roller, which is supported in crotches on the end of the arms V, pivoted in the bracket v at each end of the ink-fountain.

W is the lowermost ink-roller, which is in the fountain itself and upon which normally rests the intermediate roller U, which itself normally is free of the major roller O.

X is the bottom plate of the fountain, which is supported at one edge by the side of the fountain and at the opposite edge by a longitudinal bar x and set-screws x', extending through the bars, whereby such plate is adjusted to any desired position in relation to the roller. The ink is held immediately above the plate X. The roller U is provided with a spindle u, upon which it rotates, and the roller W with a spindle w.

In order to provide for the turning of the bottom roller W in the fountain, so as to feed the ink, I provide on the end of the spindle w an arm v', having a slot v². The upper end of the arm is provided with a cam projection v³ and has pivoted inside of the projection a dog v⁴, which normally engages with the ratchet-wheel v⁵, secured on the spindle inside of the arm.

Y is a link connected at one end to the arm n, secured to the shaft N, and at the opposite end having a bolt extending through the slot v² of the arm v', the end of the bolt being provided with a small handle y, whereby the position of the connection of the link Y to the arm v' may be very quickly changed without the necessity of using a wrench, so that the throw of the arm, and consequently of the pawl, may be regulated to a nicety.

As the inking-rollers are moved through the pivoted bar M and mechanism hereinbefore described it will be seen that upon every such swinging movement the motion will be communicated, through the arm n, link Y, and arm v' and pawl v⁴ and ratchet-wheel v⁵, to the ink-roller, thereby serving to turn it intermittently. The cam-shaped projection

*v*³ will also be raised, so as to pass beneath the arm *V*, and thereby intermittently raise the ink-roller *U*, journaled in the arms, from contact with the lower roller into contact 5 with the major roller *O*, thereby carrying the ink to the latter roller.

In order to adjust the bed-plate *L* to a nicety, I provide at each end thereof the wedge-shaped bars *l*', which rest upon the inwardly-projecting ribs *a* at the interior of the frame and extend into corresponding grooves at the outer edges of the bed-plate.

In order to adjust the bars *l*', I secure on the end a collar *l*², within which extends the spindle *l*³, which is provided with an ordinary annular groove, into which extends a pin from the collar, this being an ordinary construction and utilized in order to permit rotation of the spindle.

20 The spindle *l*³ is threaded at the outer end and provided with a hand-wheel *l*⁴ and a locking hand-wheel *l*⁵, and by means of the hand-wheel *l*⁴ the bed-plate *L* may be raised and lowered as desired and with a very fine adjustment, so that the impression may be regulated to a nicety.

25 The feeding-table *D* is provided with gage-fingers *Z*, held on the cross-rod *z*, which is bent at the end into arms *z'*, pivoted at *z*² at each side of the table upon the brackets *z*³. A rod *z*⁴, supported in suitable guides *z*⁵, extends underneath the front end of the arm and downwardly, as shown, being bent at the lower end, so as to extend over the cam *z*⁶, secured on the counter-shaft *C*. The cam *z*⁶ is provided with a drop *z*⁷. The spring *z*⁸ rests upon the front ends of the arms *z'* at the top. It will thus be seen that as the shaft *C* and cam revolve in the direction indicated by arrow the gage-fingers will be forced down, so as to stop the paper, and when the end of the rod falls over the drop *z*⁷ will permit of the paper being grasped by the gripping-fingers of the cylinder *E*, the connection of which I 45 shall presently describe, as the gage-fingers are then raised.

50 I have hereinbefore described that the shaft *F* is journaled at each end in the eccentric sleeves *f* in the standard *G*. Such standards *G* slide upon the ways *G'*.

55 I shall now describe the manner in which the paper is fed and wound upon the cylinder preparatory to being printed and carried to the delivery gripping-fingers, whereby it is removed onto the delivery-table. (Shown in dotted lines at the left-hand side of Fig. 2.) The cylinder *E* is a hollow cylinder having the ends secured to the shaft *F* and is provided with a longitudinal opening *e*, extending from end to end thereof, and end slots *e'* and *e*².

60 *E*' is the gripping-bar, which is provided with a series of gripping-fingers curved in form and having the edge normally resting and extending over the edge of the opening *e*. The cylinder *E* is shown in its normal position in proximity to the table. The grip-

ping-bar *E*' is provided at each end with the pins *e*³ and *e*⁴, which extend through the slots *e'* and *e*², respectively.

70 *e*⁵ and *e*⁶ are arms pivoted outside the ends of the cylinder *E* upon the rod *e*⁷, which extends through the cylinder. The pins *e*⁸ and *e*⁹ extend through the slots *e*⁸ and *e*⁹ in the arms *e*⁵ and *e*⁶. It will be noticed that both 75 arms are substantially L-shaped and that the arm *e*⁶ is provided with an extension from which projects outwardly a pin *e*¹⁰.

80 *S* is an arm pivoted on the cross-rod *9* and provided with an inwardly-extending end *10*, which is designed to coact in the manner hereinafter described with the pin *e*⁸. *11* is an arm secured to the same rod and provided with an inclined end *12*, which is reversely inclined as to direction of rotation to that of 85 the inclined end *10*.

85 The gaging-fingers *Z*, hereinbefore described, are so timed to operate to raise to allow of the sheet to be grasped when the cylinder *E* revolves around into the position shown 90 in full lines in Figs. 1, 2, 3, and 4 in order to connect the sheet to the cylinder that it may be wound around the same and printed as the cylinder traverses from the feed-table to the delivery-table. The gripping-fingers 95 therefore have to be raised in order to allow the edge of the sheet fed to extend beneath them, so that the fingers may be dropped down upon the edge of the sheet. To raise the fingers and to allow of them to drop, the 100 mechanism hereinbefore described is utilized, which operates as follows: As the cylinder continues to rotate in the direction indicated by arrow and approaches the feed-table the pin *e*¹⁰ on the end of the arm *e*⁶ mounts the 105 inclined end *12* of the arm *11*, thereby throwing the pins *e*³ and *e*⁴ on the ends of the gripping-bars and extending through the slots in the arms *e*⁵ and *e*⁶ upwardly, thus causing the gripping-fingers to raise from the cylinder 110 and pass over the edge of the sheet. When the pin *e*¹⁰ has passed over the inclined end *12*, the arm *e*⁶ drops, thereby allowing the pins *e*³ and *e*⁴ to recede in their respective slots *e'* and *e*² and the gripping-fingers to drop 115 upon the edge of the sheet. At this juncture the cylinder starts to rotate in the opposite direction to that indicated by arrow in Figs. 5 and 5', carrying with it the sheet of paper from the feeding-table, which winds 120 around the cylinder until the cylinder has made one revolution in approaching the opposite end of the bed. At this juncture the pin *e*³ in the slot will strike and rise upon the inclined end of the arm *8* and mount into the 125 position shown in Fig. 5^a and then drop. The cylinder still continues to revolve until it reaches the limit of its stroke. When the pins *e*³ and *e*⁴ have raised, as hereinbefore described, it necessarily follows that the gripping-fingers have also raised and released this edge of the sheet, and the gripping-fingers in 130 passing around leave such edge of the sheet free as far as they are concerned, but to be

grasped by the delivery-fingers, which I shall presently describe. When the cylinder has reached the limit of its stroke, as indicated, the pin e^4 passes underneath the inclined end 10 of the arm 8, and consequently does not affect the gripping-bar, and the cylinder finally reaches the forward limit of its stroke in proximity to the feed-table, whereupon the same operation is repeated continuously during the 10 process of printing.

In order to insure of the gripping-fingers dropping after being released upon each raising, I provide a pair of helical springs 13, extending over the outer side of the gripping-bar and secured at the opposite end to the shaft. As the cylinder rotates and arrives at the position shown in dotted lines in Fig. 2 it is necessary to hold the sheet up away from the periphery of the cylinder in order that 15 such sheet may be grasped by the delivery-fingers, and in order to allow of this I provide a cross-bar 14 with upwardly-extending fingers 15 and downwardly-extending arms 16 at the end, which project through the bottom 20 of the cylinder and are designed to come in contact with the track, so as to raise the fingers at this juncture, and consequently the sheet. It may be stated that I of course arrange these fingers directly underneath the 25 gripping-fingers, as otherwise the sheet would be punctured.

In order to deliver the sheet when it has been brought by the cylinder and gripping-fingers forward into proximity with the end 30 of the bed of the machine and released by such gripping-fingers, I provide the following mechanism:

17 is a rock-shaft secured in the bracket extensions A' of the frame.

40 18 represents arms secured to the ends of the rock-shaft and extending normally above the level of the delivery-table in an oblique direction, as indicated.

45 19 is a cross-rod connecting the upper ends of the arms 18.

50 20 is the lower gripping-bar, which is provided with a series of fingers 21 and the journal-rings 22, one of which is provided with a projection 23, which is designed to come in contact with a projection 24 on the collar 25 to limit the fall of the fingers.

55 26 is the upper gripping-bar, provided with a series of fingers 27 and journaled on the rod 19 by the end rings 28.

50 29 is a spring encircling the rod 19 and secured at one end to the same and having the opposite end extending over the gripping-bar 26, so as to have a normal tendency to force the gripping-fingers 27 downwardly.

60 30 is a spring on the rod 19, secured at one end thereto and having the opposite end extending under the gripping-bar 20, the normal tendency of the spring being to force the gripping-bar and the fingers 21 thereof upwardly.

65 27 and 21' are the end fingers, which are

provided with laterally-extending pins 27² and 21², respectively.

31 is a rod connected to the finger 21' and extending down in suitable bearings opposite 70 the arm 18, the lower end being bent and extending under a pin 32. When the arms 18 are being brought forward to grip the edge of the sheet by the mechanism, as hereinafter described, the lower bent end of the arm 31 75 is free from the pin 32; but when the upper end of the arm has reached the limit of its rearward stroke the bent end of the rod 31 contacts with the pin 32, thereby pulling down the finger 21' and releasing the sheet 80 and allowing it to drop upon the delivery-table. The arms 18 are connected by the rod 33 to the lower end of the lever 34, which is pivoted at the top at 35 on the frame and is provided intermediately with a roller 36, 85 which works in a cam-groove 37 in the opposite gear-wheel C'. The shape of this cam is such that the arms 18 are caused to rest for a considerable period of the rotation of the wheel C', which period is that occupied by 90 the traversing of the cylinder from the point shown in dotted lines to the feeding-table and back again to such point. The remaining portion of the cam operates upon the roller 36, so as to bring the sheet-delivery fingers 95 toward the cylinder when it reaches the dotted position and then bring it back again. The shape of the cam 37, however, is such that the delivery-fingers travel at a uniform rate with the cylinder to the extreme end of 100 the rearward movement of such cylinder or during the period that the gripping-fingers are removing the sheet from the cylinder.

It will be seen that the normal tendency of the springs 29 and 30 is to keep the fingers 105 21 and 27 close against each other, and it is essential that a means be provided to open the fingers to grasp the sheet as well as to open the fingers to release the sheet. In order to effect this, it will be noticed that I provide a separating-cam 38, attached to or forming part of the supporting-rollers 39, which run on the upper tracks G². These rollers 39 at each end, as the cylinder and the shaft thereof revolve, of course necessarily support 110 the cylinder during its movement across the bed of type, and the cam 38 is so arranged and timed that when the gripping-fingers meet the cylinder this cam 38 will pass between the pins 27² and 21², thereby separating the fingers and allowing them to straddle the edge of the paper. As soon as the cam has passed between the pins 27² and 21² the fingers 27 and 21 are forced by their springs 115 together, so that the edge of the sheet is securely gripped, whereupon it is carried away by the rearward movement of the sheet-delivery device hereinbefore described.

I find it preferable to provide a pressure-roller g near each end of the cylinder, which 120 is designed to press against the edge of the printed sheet of paper and prevent it from

falling back from the cylinder during the period between when the edge of the sheet is loosened by the gripping-fingers on the cylinder and the time it is being grasped by the

5 sheet-delivery gripping-fingers. These rollers are secured on the ends of the arms g' , pivoted on the bearing-standard G , and are held up to the cylinder by the springs g^2 .

It will be noticed, as hereinbefore described, 10 that the spindle F of the cylinder is supported at the ends in the eccentric collars or sleeves f in the bearing-standards G . It is necessary in the backward movement of the cylinder after having brought the paper over 15 the type to receive the impression to raise such cylinder in order to escape the type. In order to effect this, I provide projecting arms 40 , having lateral extensions 41 , through which extends set-screw 42 . Upon one lateral 20 extension 41 is formed a bearing 43 , which receives the curved end of the rod 44 , which extends through the guiding-lug 45 on the side of the machine and is provided with an end stop 46 . As the cylinder is caused to move 25 toward the delivery end of the bed after the printing has been effected, the stop 46 coming in contact with the lug 45 pulls back upon the arm 40 , thereby turning the sleeve or collar f in its bearing in the standards G , so that 30 the long radius of the eccentric is lowermost, thereby raising the cylinder in its movement clear of the bed, in which position it will remain as the retrograde movement is being effected. At near the limit of the retrograde 35 movement, however, the arms 40 , which are now in a substantially vertical position, strike against the pivoted rocking detents 47 , which are held rigidly against the pins 48 , and thereby knock the arm 40 backward again into its 40 initial position shown in Figs. 1 and 6. This operation is repeated upon each reciprocating movement of the cylinder.

In order to provide a means whereby should one sheet be missed through the fault of the 45 attendant of the machine, I provide the following simple device, or what is technically known as the "throw-off," in order to raise the cylinder clear of the type and prevent it printing on the tympan or pad on the cylinder.

50 49 represents catches secured on each end of the rod 50 , which is suitably pivoted in the side bars of the feed-table, as indicated. The catch 49 is provided with a weighted handle 51 , and the rear end of the catch is designed to be brought into engagement with the notch 52 in the upper end of the rocking detent 47 when a sheet has been missed. The result is that the arms 53 , forming part of the eccentric sleeves f at each end of the spindle F , come in contact with the bottom end of such rocking detents, and thereby, as such rocking detents are locked, the arms 53 are turned 55 downwardly as to direction of movement of the cylinder, so as to throw the longer radius of the eccentric sleeves f lowermost, and thereby raise the cylinder above the height of the

bed, so that such cylinder when no sheet is on it will pass in such elevated position backward and forward to its initial position again 70 without any printing being effected.

It is of course to be understood that when the arm 53 is tilted it will be tilted sufficiently so that it will pass under the rocking detent. As the arm 53 moves with the cylinder in its movement to the feeding-table again it will again pass under the lower end of the rocking detent at each side; but the arm 40 , which is now raised, will strike against the now locked rocking detent, whereupon the 75 arm 40 on each side will be lowered into its initial position, ready for the next forward movement of the cylinder, which is thereby lowered, ready to give the impression. The catch 49 may be of course raised from engagement with the notch at the top of the 80 rocking detent at any time after the cylinder has passed such detent in its movement toward the delivery-table.

What I claim as my invention is—

1. In a printing-press, the combination with the feeding-table, of the gaging-fingers located opposite the inner end of the table, the rods having bent ends pivotally supported, the springs normally pressing on the bent 95 ends or arms, so as to hold up the gaging-fingers and means for intermittently overcoming the pressure of the springs, so as to press the fingers to the edge of the table as and for the purpose specified.

2. In a printing-press, the combination with the feeding-table, of the gaging-fingers located opposite the inner end of the table, the rods having bent ends pivotally supported, the springs normally pressing on the bent 105 ends or arms, so as to hold up the gaging-fingers, the rod extending upwardly underneath the front end of the bent arms, suitable guides for supporting the same and the drop-cam on the main shaft with which the bent end of 110 the rod is arranged to engage as and for the purpose specified.

3. In a printing-press, the combination with the feeding-table, of the hollow cylinder journaled in suitable bearing-standards, means for imparting a rotary and reciprocating movement to the cylinder, a gripping-bar extending from end to end of the hollow cylinder and provided with gripping-fingers designed to extend through a slot in the cylinder and overhang one edge thereof and means for raising the gripping-bar, so as to raise the 120 fingers in order that they may be lowered to grasp the overhanging sheet at the edge of the feeding-table as and for the purpose specified.

4. In a printing-press, the combination with the feeding-table, of the hollow cylinder journaled in suitable bearing-standards, means for imparting a rotary and reciprocating movement to the cylinder, a gripping-bar extending from end to end of the hollow cylinder and provided with gripping-fingers designed to extend through a slot in the cylinder and overhang one edge thereof, means for

raising the gripping-bar, so as to raise the fingers and means for lowering the gripping-fingers so that they may grasp the edge of the overhanging sheet on the feeding-table as and for the purpose specified.

5. In a printing-press, the combination with the feeding-table, of the hollow cylinder journaled in suitable bearing-standards, means for imparting a rotary and reciprocating movement to the cylinder, a gripping-bar extending from end to end of the hollow cylinder and provided with gripping-fingers designed to extend through a slot in the cylinder and overhang one edge thereof, pins attached to or forming part of the ends of the gripping-bar and extending through slots on the ends of the cylinder and means for raising and lowering the pins in the slots as and for the purpose specified.

20. 6. In a printing-press, the combination with the feeding-table, of the hollow cylinder journaled in suitable bearing-standards, means for imparting a rotary and reciprocating movement to the cylinder, a gripping-bar extending from end to end of the hollow cylinder and provided with gripping-fingers designed to extend through a slot in the cylinder and overhang one edge thereof, pins attached to or forming part of the ends of the gripping-bar and extending through slots on the ends of the cylinder and the arms pivoted on a rod extending through the cylinder and provided with slotted ends through which the pins of the gripping-bar extend and means for controlling the tilting of such arms as and for the purpose specified.

7. In a printing-press, the combination with the feeding-table, of the hollow cylinder journaled in suitable bearing-standards, means for imparting a rotary and reciprocating movement to the cylinder, a gripping-bar extending from end to end of the hollow cylinder and provided with gripping-fingers designed to extend through a slot in the cylinder and overhang one edge thereof, pins attached to or forming part of the ends of the gripping-bar and extending through slots on the ends of the cylinder and the arms pivoted on a rod extending through the cylinder and provided with slotted ends through which the pins of the gripping-bar extend, a cross-rod supported on the bearing-standards of the cylinder, an arm carried by the same and having an inclined inner end, which extends into proximity with the pin at one end of the gripping-bar next the short arm on the end of the cylinder and designed to coact therewith as and for the purpose specified.

8. In a printing-press, the combination with the feeding-table, of the hollow cylinder journaled in suitable bearing-standards, means for imparting a rotary and reciprocating movement to the cylinder, a gripping-bar extending from end to end of the hollow cylinder and provided with gripping-fingers designed to extend through a slot in the cylinder and overhang one edge thereof, pins attached to

or forming part of the ends of the gripping-bar and extending through slots on the ends of the cylinder and the arms pivoted on a rod extending through the cylinder and provided with slotted ends through which the pins of the gripping-bar extend, a cross-rod supported on the bearing-standards of the cylinder, an arm carried by the same and having an inclined inner end, which extends into proximity with the pin at one end of the gripping-bar next the short arm on the end of the cylinder and designed to coact therewith and an arm supported on the cross-arm and located at the opposite end of the cylinder and provided with an inclined end, a pin on the extended slotted bent arm at the opposite side of the cylinder designed to coact with the inclined end of the arm on the cross-rod when the cylinder is approaching the limit of its stroke toward the delivery-table as and for the purpose specified.

9. The combination with the cylinder and track for the inking-rollers and the grippers held in the cylinder, of the bar provided with upwardly-extending fingers located in the cylinder underneath the grippers and having depending ends extending through holes in the cylinder and designed to come in contact with the track when the grippers are being raised as the cylinder approaches the limit of its stroke toward the delivery-table as and for the purpose specified.

10. The combination with the cylinder and the spindle thereof and the slide standards supported on suitable guideways and means for imparting a reciprocating movement to the standards, of the eccentric sleeves extending through the standards and forming a bearing for the spindles, an arm attached to or forming part of each sleeve and extending outwardly therefrom, a lateral projection to such arm designed normally to rest upon the top of the bearing-standard and having a bearing at one end, a rod extending through such bearing and provided with a stop at the opposite end and a guiding-lug support for the rod on the frame as and for the purpose specified.

11. The combination with the cylinder and the spindle thereof and the slide standards supported on suitable guideways and means for imparting a reciprocating movement to the standards, of the eccentric sleeves extending through the standards and forming a bearing for the spindles, a supplemental arm extending outwardly from the sleeve and a rocking detent pivoted in the frame, a pin for controlling the movement of the rocking detent in one direction only and means for locking the detent at the upper end as and for the purpose specified.

12. The combination with the cylinder and the spindle thereof and the slide standards supported on suitable guideways and means for imparting a reciprocating movement to the standards, of the eccentric sleeves extending through the standards and forming

a bearing for the spindles, a supplemental arm extending outwardly from the sleeve and a rocking detent provided with a notch at the upper end, a pin-stop for the detent to allow 5 of its movement in one direction only and a pivoted catch on the frame provided with a suitable end to engage the notch at the top of the rocking detent as and for the purpose specified.

10 13. In a printing-press the combination with the cylinder, of the standards therefor,

supporting-rollers for the cylinder, tracks upon which the rollers run, cam projections on the rollers, delivery-arms, and gripper-fingers mounted therein, the cams on the rollers being designed to separate the gripping-fingers to receive the sheet, substantially as described. 15
